IRVING KIMBALL, OF BROOKLINE, MASSACHUSETTS, ASSIGNOR TO GLOBE TECHNOLIAN CORPORATION, OF BOSTON, MASSACHUSETTS, A CORPORATION OF MASSACHUSETTS.

DIAPHRAGM.

Application filed July 6, 1925. Serial No. 41,626.

- This invention relates to a diaphragm for use in sound reproducing apparatus, and has for an object to provide a novel and superior construction of diaphragm, which is particularly useful in place of the ordinary steel, mica or rubber diaphragms used in such apparatus, and by which sound and particularly music, of superior tone and quality may be reproduced.
- With this object in view, the invention consists in the diaphragm hereinafter described and particularly defined in the claims at the end of this specification.
- In the drawing illustrating the preferred embodiment of the invention, Figure 1 illustrates more or less diagrammatically a loud speaker unit of the balanced armature type at present upon the market, and in which the present construction of diaphragm is embodied; Fig. 2 is an exploded view of the laminations comprising the present diaphragm; and Fig. 3 is a sectional view illustrating the usual form of phonographic reproducer unit with which the present diaphragm may be used with advantage.
- In the reproduction of sound by diaphragm vibration, and particularly of music, as in phonographic and radio work, the distortion of the sound accompanying the performance of the different forms of the reproducing apparatus at present upon the market is noticeable particularly to the expert and detracts from the accuracy with which the original sound or music may be reproduced in details of quality and tone. I have determined that a large amount of this distortion is caused by the natural period of vibration in the diaphragm itself, and that as a consequence of this vibration inherent in the diaphragm itself because of its construction, the sound or musical reproduction is accompanied by distortion which I believe to be the cause of the production of false harmonics or over-tones.
- In accordance with the present invention a diaphragm is constructed to eliminate, to a large extent, this objectionable distortion in tone, and the inherent vibration resulting from the natural period of vibration in the diaphragm itself, and the consequent production of these objectionable false over-tones and false harmonics, and for this purpose I have discovered that a laminated structure involving opposing sheets of rubber or rubber composition applied and adhering to the opposite surfaces of a diaphragm core, and which may be covered by fibrous material in sheet form, possesses the property of eliminating to a large extent the production of these objectionable false harmonics and false over-tones when the diaphragm is used in sound reproducing apparatus in radio, telephone and phonographic work, so that the tone produced is that of the original voice or music.
- Referring to the drawing, 10 represents a diaphragm embodying the present invention, and which comprises a laminated structure formed of a plurality of individual sheets of different material, and which is diagrammatically illustrated in an exploded position in Fig. 2. Referring to Fig. 2, the diaphragm preferably comprises a steel core 12, although mica or rubber diaphragms of a relatively stiff nature may, for certain purposes, be found suitable. The steel core 12 is preferably of the construction of the ordinary steel diaphragm used in loud speaker units in radio work, and the core 12 is, in accordance with the present invention, provided upon its opposite surfaces with relatively thin sheets 13, 14 of rubber or rubber composition, and preferably of unvulcanized rubber, and the rubber sheets 13, 14 are preferably vulcanized or cemented upon the steel diaphragm 12, as will be described. The outer surfaces of the rubber sheets 13, 14, may, and preferably will be, covered with thin sheets of fibrous material, and I have found that excellent results may be secured by providing one sheet 15 of paper, the pores of which may be filled with a suitable lacquer of any usual or preferred composition, to prevent it from absorbing moisture, and a second sheet 16 of chamois. In applying the rubber sheets 13, 14 and the fibrous sheets 15 and 16, I prefer to form the sheets of a shape corresponding to the central core or diaphragm 12, and to assemble the sheets under heat and pressure, by which the rubber sheets 13, 14 are caused to melt to a certain degree sufficient to cause them to firmly adhere to the surfaces of the sheet 12, and preferably to become vulcanized and to adherently secure the fibrous sheets 15, 16 to the core 12, producing a laminated structure in which the different lamina-

tions are securely affixed to one another, and enabling the diaphragm to function in the desired manner, but without the objectionable production of false harmonics and 5 over-tones above referred to.

- The rubber layers 13, 14 appear to have the effect of preventing the laminated diaphragm from producing the false over-tones and at the same time do not detract from 10 the efficiency of the diaphragm, so that when used for radio reception in a loud speaker unit, the diaphragm functions to faithfully reproduce the original music or voice.
- 15 For radio work, and particularly as the diaphragm of loud speaker units such as is illustrated diagrammatically in Fig. 1, the present diaphragm is preferably arranged with the chamois 16 upon the inside, and I 20 have found that by so arranging the chamois sheet 16, the vibrations produced during the operation of the unit are caused to pass to the amplifying horn or member of the unit without any distortion resulting from echoes 25 or other causes, and as a result the tone produced is deepened without blurring or distortion, and is a practically perfect reproduction of the original sound or music.

In Fig. 1 a portion of a loud speaker unit 30 for radio reception is shown with portions of the electro-magnetic mechanism for its actuation. The details of the latter form of themselves no part of the present invention, and may comprise any of the known 35 forms now upon the market. The illustrated form is the well-known balanced armature type wherein an armature 30 pivoted at 32, is oscillated up and down and through a link connection 33 operates in the usual 40 manner to cause the diaphragm 10 to vibrate in accordance with the music or voice being reproduced.

Similarly, the present construction of 45 laminated diaphragm is particularly useful for phonographic work and, as illustrated in Fig. 3, the diaphragm unit comprises the usual casing 40 within which the present diaphragm 10 is secured in the usual manner by a clamping ring 42 with the chamois 50 layer 16 of the diaphragm on the inside, or in a position adjacent to the socket 43 into which the end of the tone arm 44 of the phonograph fits. The usual form of stylus 46 is connected by the usual form of bracket 55 47 to the center of the diaphragm 10, and as the stylus travels upon the record, the vibration imparted to the diaphragm 10 causes the reproduction of the sound or music in the usual manner, except that the laminated 60 construction of diaphragm above described avoids the production, or at least reduces to a minimum the production, of false harmonics and over-tones which heretofore have

accompanied the operation of the usual form of diaphragm, and causes distortion, harshness and objectionable reproduction of the 65 original voices or music.

While the preferred embodiment has been illustrated and described, it is to be understood that the invention may be embodied 70 in other forms within the scope of the following claims.

Having thus described the invention, what is claimed is:

1. A diaphragm for sound reproducing 75 apparatus comprising a laminated structure having a relatively stiff circular central core, solid layers of thin sheet rubber upon opposite surfaces thereof, adhesively affixed to the core, and layers of fibrous material covering said rubber layers and adhesively secured thereto.

2. A diaphragm for sound reproducing apparatus comprising a laminated structure having five layers of equal area and composed of a steel core, rubber layers upon opposite surfaces thereof and adhesively secured thereto, a fibrous layer covering one of said rubber layers, and a chamois layer 90 covering the other of said rubber layers.

3. A diaphragm for sound reproducing apparatus comprising a laminated structure provided with an outer layer of chamois.

4. A diaphragm for sound reproducing apparatus comprising a core provided with 95 material on the surfaces thereof for reducing the tendency of the diaphragm to vibrate at a natural period, comprising relatively thin sheets of rubber adhesively affixed to and covering said surfaces of the core, 100 said core being of such dimensions as to completely separate the two rubber sheets.

5. In a sound reproducing apparatus having provision for conducting sound waves to an amplifier, a laminated diaphragm 105 comprising a core and outer layers of fibrous material at least one of which is chamois and which one is adjacent the amplifier.

6. In a sound reproducing apparatus having provision for conducting sound waves to 110 an amplifier, a laminated diaphragm comprising a steel core with covering layers of paper at one side and chamois at the other side each being secured to the core by an interposed layer of sheet rubber, and having 115 said chamois layer facing the amplifier.

7. The method of making laminated diaphragms which comprises assembling a disk of unvulcanized rubber against each side of a circular core and a disk of fibrous material against each disk of rubber, then applying heat and pressure to cause adherence of all the layers through vulcanization of the 120 rubber sheets.
